DISPENSER FOR TOOTHPICKS AND THE LIKE

Maxie M. Sullivan, Lubbock, Harry R. Garrett and James F. Garrett, Pampa, Tex.

Application November 30, 1954, Serial No. 33,337

Term of patent 14 years

(Cl. D52—2)

Fig. 1.

Fig. 4.

Fig. 2.

Fig. 5.

In the drawings:

We claim:

The ornamental design for a dispenser for toothpicks and the like, as shown.
